Patented June 13, 1922.

Fig. 1.

UNITED STATES PATENT OFFICE.

CHARLES A. ERICKSON, OF CHICAGO, ILLINOIS.

SALES-CHECK HOLDER AND PUNCH.

1,419,621.

Specification of Letters Patent. Patented June 13, 1922.

Application filed October 14, 1921. Serial No. 507,776.

To all whom it may concern:

Be it known that I, CHARLES A. ERICKSON, a citizen of the United States, residing at Chicago, in the county of Cook and State of Illinois, have invented certain new and useful Improvements in a Sales-Check Holder and Punch, of which the following is a specification.

My present invention relates to improvements in a handy and novel holder and punching or notching device for sales checks, such as are used in restaurants, at soda fountains, in ice cream shops and other places, for indicating or checking the price of meals, 15 drinks and other purchases, as well as the number of waiter or salesman.

The principal object of the invention is to combine in a unitary, compact and handy form, for pocket and manual use, a holder 20 for such checks, a punching or notching device to indicate on such checks the amount to be paid to the cashier, and a container for the clippings produced by notching or punching the checks, so that the same will 25 not fall on and litter the floor.

Another object is the provision of a device of the above named general character, which shall be of such construction that it can be held in, and the punch manipulated by, 30 either hand of the user, and so that the checks can be detached one at a time from the book or pad thereof held by the device, and conveniently placed in position for being punched or marked.

Still another object is to simplify the construction, to lessen the cost of manufacture of devices for the purpose set forth, and to provide positive means for holding the blocks or pads of checks in position on the 40 devices.

Other objects and advantages of the invention will become obvious from the following description and explanation.

In the accompanying drawing, which 45 serves to illustrate an embodiment of the invention—

Fig. 1 is a plan view of the device showing a block of sales checks held thereby ready for use.

Fig. 2 is a central longitudinal sectional view taken on line 2—2 of Fig. 1, and

Fig. 3 is an end elevation looking into the socket or check holding compartment of the device.

Like numerals of reference refer to corresponding parts throughout the different views of the drawing.

The body of the device is designated as a whole by the reference numeral 5, and consists of an elongated support or floor 6 having at each of its side edges an up-turned flange 7 or side piece, which are widened towards their rear ends as is clearly shown in Fig. 2 of the drawing. The body of the device is by preference made of a single 65 piece of sheet metal and has one of its sides 7 bent at its rear end to lie transversely across the device as shown at 8 in Fig. 1 of the drawing. This rear end piece 8 is provided at about its middle with a vertically disposed angular guide-way 9 which presents its apex rearwardly and has at a suitable distance from its lower end a forwardly extended opening 10 the edges of which are inwardly beveled or converged 75 as shown. The opposite flange or side 7 of the body of the device is provided at its rear end with a transversely disposed part 11 which is located forwardly of the transverse portion 8 of the other side member, and fastened thereto by means of rivets 12 or otherwise. The portion 11 has a cut-away portion or opening 13 extended from its middle to the floor or support 6 for the passage of 80 clippings punched from the checks as will 85 be presently explained. The upper edge of the transverse portion 11 is of a width to fit snugly between the sides 7 when bent forwardly as shown in Figs. 1 and 2, thus forming the top or overhanging portion 14 of the 90 casing or socket 15, the flanges forming the sides of said casing or socket and the transverse portions 8 and 11, the rear end thereof, while the floor 6 comprises the bottom of the said casing.

The front end of the top 14 is bent downwardly to provide a toothed flange 16 employed for the purpose of engaging the stub 17 of a block of sales checks 18 of the type usually employed in restaurants, and like 100 places. The front portion of the top 14 has punched out and extended downwardly a

tongue 19 which, together with a tongue 20 punched out of the floor 6 and extended upwardly, form stops against which the rear end of the stub of the block of checks will 5 rest. Besides, the tongue 20 will form a closure for the front end of a box-like receptacle for the clippings or punchings from the checks when the stub of the same is removed from the forward or open end of the 10 casing 15 or socket therefor.

Each of the sides 7 is provided at its upper edge just rearwardly of the front edge of the top 14, with a lip 21 which are bent over to lie flatly on the top 14 so as to prevent 15 its displacement outwardly. The floor 6 of the body has punched therefrom a longitudinally extended arm or bar 22 which is provided near its free end with teeth 23 for engagement with the lower surface of the 20 block of checks. Thus it will be seen and understood that, although the body 5 comprises several members, they are all made of one piece, and can be fashioned into the structure shown in Fig. 2 and above described, without 25 the employment of rivets except those indicated by the numerals 12 for securing the transverse portions 8 and 11 together.

Located in the slot 24 in the floor of the body formed by punching out the arm 22, is 30 an operating lever 25 for said arm, which is mounted on a pivot 26 transversely disposed with respect to the body and journaled in the sides 7 thereof at or near the front end of the socket 15. This lever is provided at 35 its rear end with a projection 27 to contact with the lower surface of the arm 22 so that by turning the lever 25 to the position shown in Fig. 2 the teeth 23 of the arm 22 will be caused to engage the lower surface of the 40 block of checks, when said teeth are employed, and cause the upper part of the block or its stub to be engaged by the toothed flange 16 in such a way that the block will be firmly held in position between the sides 45 7 of the frame yet in such a manner that the uppermost check may be torn off along the front line of the flange 16.

Mounted in the guide 9 for vertical movement therein is a punch or plunger 28 which 50 is of the same shape in cross-section as the guide 9 and has its lower edges inwardly or forwardly beveled as at 29, to co-act with the edges of the opening 10 in said guide to cut-away portions of the checks, which portions will fall into the receptacle below and forwardly of the opening 10 and there be confined until it is desired to empty the receptacle therefor, which can be done by releasing the stub 17 and removing the same, 55 when it is apparent that the clippings can be emptied through the space between the members 19 and 20, which as before stated, form stops for the rear end of the stub of the block.

60 The upper end of the plunger 28 is pro-

vided with a forwardly disposed thumb-rest 30 from which is extended downwardly through an opening in the top 14 of the casing a rod 31 which preferably has on its lower end a head or enlargement 32 to prevent its dis-location. Surrounding the rod 31 and resting at one of its ends against the top 14 and at its other end against the thumb-rest 30 is a coiled spring 23 which acts to retract the plunger 28 to its normal 75 position as shown in Fig. 2, after it has been pressed downwardly and in the operation of notching the check.

After one of the checks has been detached from the block thereof, it is manifest that 80 the said check can be placed cross-wise of the rear end of the body with one of its edges in the opening 10 of the guide thereon so that the numerals indicating the price to be paid to the cashier may be cut out by depressing the plunger.

It will be observed in Fig. 2 of the drawing that the operating lever 25 is of the bell-crank type, and that when positioned as shown in said figure, the arm 22 will be positively prevented downward movement or movement in a direction opposite the top of the casing. When it is desired to remove the stub of the block of checks, this can be done by reversing the position of the operating 95 lever 25 which will permit the arm 22 to be moved downwardly or outwardly and thus release the said stub.

Having thus fully described my invention, what I claim as new and desire to secure by Letters Patent is—

1. A device of the class described, consisting of an elongated body having at one of its ends an overlying part and provided with a longitudinal arm movable at one of its 105 ends under said overlying part, and means carried by the body and co-acting with said arm to move the same toward said part and to lock it against movement in the opposite direction.

2. A device of the class described, consisting of an elongated body having at one of its ends an overlying part and provided with a longitudinal arm movable at one of its 115 ends under said overlying part, and a lever longitudinally disposed under said arm and adapted for co-action therewith for moving it towards said part and for locking it against movement in the opposite direction.

3. In a device of the class described, the 120 combination with an elongated body having one of its ends formed into a rectangular casing having its front end open to provide a socket, of stop members within said casing rearwardly of its front end, the floor of said body having an arm extended longitudinally therewith and movable at one of its ends under the top of said casing, and a bell-crank-lever fulcrumed on the body with its arms adapted to engage said movable arm on each 125 130

side of the fulcrum of said lever for positively holding said arm in a given position.

4. The combination with an elongated channeled body having an overlying part at 5 one of its ends, of an arm extended longitudinally with said body and having one of its ends movable under said overlying part, and

a bell-crank-lever fulcrumed on the body with its arms adapted to engage said movable arm on each side of the fulcrum of said 10 lever for positively holding said arm in a given position.

CHARLES A. ERICKSON.
